United States Patent Office

Des. 194,020
Patented Nov. 13, 1962

194,020

SURVEYOR'S TOOL HOLDER OR THE LIKE

Donald G. Jarman, Portland, Oreg., assignor of one-half
to Frances E. Woertendyke, Portland, Oreg.

Filed Nov. 27, 1961, Ser. No. 67,715

Term of patent 3½ years

(Cl. D3—26)

FIGURE 1 is a front elevational view of a surveyor's tool holder or the like showing my new design.

FIGURE 2 is a side elevational view of FIGURE 1.

I claim:

The ornamental design for a surveyor's tool holder or the like, substantially as shown.
